(57) **CLAIM**

The ornamental design for a stem wall movable base board as shown and described.

DESCRIPTION

FIG. 1 is a perspective view of a stem wall movable base board showing my new design;

FIG. 2 is a front perspective view thereof;

FIG. 3 is a rear perspective view thereof;

FIG. 4 is a front plan view thereof;

FIG. 5 is a rear plan view thereof;

FIG. 6 is a left side plan view thereof;

FIG. 7 is a right side plan view thereof;

FIG. 8 is a bottom plan view thereof; and,

FIG. 9 is top plan view thereof.
